UNITED STATES PATENT OFFICE.

ANNABELL C. BULL, OF PEORIA, ILLINOIS.

DESIGN FOR A BELT.

SPECIFICATION forming part of Design No. 22,552, dated June 27, 1893.

Application filed February 24, 1893. Serial No. 463,646. Term of patent 3½ years.

To all whom it may concern:

Be it known that I, ANNABELL C. BULL, a citizen of the United States, residing at Peoria, in the county of Peoria and State of Illinois, have invented and produced a new and original Design for Belts, of which the following is a specification, reference being had to the accompanying drawing, showing a part thereof.

10 The figure shows an elevation of the design with all the particular features thereof.

The leading feature of my design consists in the belt having the shape, configuration, and ornamentation shown in the drawing.

15 In the figure A is a belt of uniform width,

and of plain band or ribbon shape in its general contour, the whole belt being cut in the shape of an obtuse angle. B, B, B, are rectangular flaps giving the lower edge of the belt a regular notched appearance.

What I claim is—

The design for a belt as herein shown and described.

In testimony whereof I affix my signature in presence of two witnesses.

ANNABELL C. BULL.
